UNITED STATES PATENT OFFICE.

GEORGE O. ZIMMERMAN, OF MASON CITY, ILLINOIS.

HOLDER FOR SPARK PLUGS.

Application filed October 29, 1921. Serial No. 511,507.

To all whom it may concern:

Be it known that I, GEORGE O. ZIMMERMAN, a citizen of the United States, residing at Mason City, in the county of Mason and 5 State of Illinois, have invented certain new and useful Improvements in Holders for Spark Plugs, of which the following is a specification.

This invention relates to devices for holding the spark plugs of the cylinders of the internal combustion engines of motor cars, when the plugs are removed from the cylinders for examination and repair. It is found difficult to hold the plugs with the 10 tools ordinarily carried, and when no vise is available. This invention consists of a small and light holder for the plugs which can conveniently be carried in the tool box of a motor car, and which can be secured 15 to any convenient portion of the car.

In the drawings, Figure 1 is a plan view of a holder for spark plugs constructed according to this invention. Fig. 2 is a cross-section through the same, taken on the line 25 2—2 in Fig. 1.

A plate 4 is provided, and 5 are hexagonal sockets of different size which project from the lower side of the plate, and which have inwardly projecting shoulders 6 at 30 their lower ends.

The spark plugs are made in standard

sizes, and two sockets are usually sufficient to engage with all the standard sizes. The spark plug when removed from the cylinder is placed in one of the sockets, as indicated 35 by dotted lines in Fig. 2. The shoulder supports the plug, and the socket prevents it revolving when a wrench is applied to it to take it apart.

The plate 4 has a flange 7 at one end, and 40 8 are bolt holes in the plate and in the flange. Any ordinary bolt is used for temporarily bolting the plate to any convenient part of the motor car. A clamping jaw 9 is arranged opposite the flange 7, and 10 is a bolt 45 arranged in holes in the flange and jaw, so that the plate can be clamped to any suitable part of the car, if this form of attachment should be found advantageous.

What I claim is:

A holder for spark plugs, comprising a flat supporting plate having a plurality of hexagonal sockets of different size for engaging with spark plugs, said plate being arranged at one end of the sockets which are 55 unobstructed and open at that end, and said sockets having inwardly projecting shoulders at their other ends for supporting the plugs in the sockets.

In testimony whereof I have affixed my 60 signature.

GEORGE O. ZIMMERMAN.
